UNITED STATES PATENT OFFICE.

GEORGE T. PEARSONS, OF NEW YORK, N. Y.

FIRE-EXTINGUISHER.

1,194,781.

Specification of Letters Patent. Patented Aug. 15, 1916,

Application filed May 31, 1916. Serial No. 100,814.

To all whom it may concern:

Be it known that I, GEORGE T. PEARSONS, a citizen of the United States, residing in the borough of Manhattan, city, county, and 5 State of New York, have invented new and useful Improvements in Fire-Extinguishers, of which the following is a specification.

This invention relates to syringes in which a stream or jet of liquid is ejected 10 from a reservoir during each outward and inward movement of a piston, and it is the object of the invention to provide improved means to obtain this result which are simple and cheap in construction, efficient in operation and adapted for fire extinguishers.

In carrying out the invention I provide a reservoir having an outlet and mount a cylinder in the reservoir with a piston to reciprocate in the cylinder, said cylinder 20 having inlets adjacent opposite ends controlled by valves opening into and closing outward from the cylinder and having outlets adjacent its ends with valves opening outward from and closing into the cylinder, 25 and provide means to connect said cylinder outlets to the outlet of the reservoir, whereby as the piston is reciprocated liquid is drawn from the reservoir into the cylinder alternately to opposite ends of the piston 30 and discharged therefrom alternately from opposite ends of the piston and out through the reservoir outlet.

In the drawing accompanying and forming a part of this specification there is 35 shown a longitudinal sectional elevation of a syringe with an embodiment of my invention applied thereto.

The embodiment of my invention shown in the drawing consists of a tank or reservoir for a fire extinguishing liquid comprising a body portion 1, preferably cylindrical in shape, and the ends 2 and 3 secured thereto as by soldering or otherwise, the end 2 having a discharge outlet 4 and the end 45 3 a filler opening closed by a plug 5, said plug being constructed with an inwardly opening and outwardly closing spring influenced check valve to permit entrance of air into the reservoir as the liquid is ejected 50 therefrom. The end 2 is preferably dished to permit of the standing of the syringe

upon a horizontal surface. Mounted in the reservoir is a piston chamber comprising a cylinder 6, preferably of less length than the reservoir as shown, the said cylinder being closed at opposite ends by heads 7 and 8, and having ports 9 and 10 through the heads to the cylinder to provide inlets to the cylinder at opposite ends, said ports having spring influenced valves 28 and 29 closing outward from and opening into the piston cylinder. The cylinder end 7 has a chamber 16 which has a port 11 connected with outlet means in the form of a tube 17 with the outlet 4 of the reservoir. Directly 65 in line with the port 11 is a port 11' leading into the end of the piston cylinder to constitute an outlet for the cylinder, said port normally being closed by a spring influenced valve 12 closing into the cylinder 70 and opening outward therefrom. A port 13 in the opposite head 8 of the cylinder communicates with the cylinder to constitute an outlet for the opposite end of the cylinder, communication between said port and 75 the cylinder being controlled by a spring influenced valve 14 closing into the cylinder and opening outward therefrom. The said port 13 is at all times connected to the chamber or casing 16 by a tube 15. The 80 piston chamber extends from the reservoir end 3, but not to the full length of the reservoir.

The cylinder 6 has a driving fit with the cylinder heads 7 and 8 and the head 8 has a bore extending therethrough of the same diameter as the bore of the cylinder 6 to constitute a continuation thereof. The piston chamber is mounted in the reservoir with the head 8 abutting against the inner 85 wall of the reservoir end 3, a flanged threaded nut 20 having screw threaded connection with said cylinder head with the flange of the nut engaging outside of the reservoir end 3 thereby clamping said end 90 between the flange of the nut and the cylinder end 8 and firmly securing the piston cylinder thereto.

A piston 18 having suitable packing is adapted to be reciprocated in the cylinder 100 6 by a rod 19 fixed at one end of the piston, the said rod extending through an opening

in the nut 20 and packing 21 retained in a recess in said nut to the exterior of the piston chamber and reservoir, and has an operating handle 22 fixed to said projecting end.

To permit of the drawing of the liquid from the lowermost part of the reservoir, I provide a tube 27 to lie adjacent the side of the reservoir and in operation below the piston ends with the ends adjacent opposite ends of the reservoir, said tube 27 being connected to the inlet ports 9 and 10 of the piston cylinder by tubes 24 and 25. To permit drawing of the liquid from either end 15 of the reservoir whether the reservoir is full or partially empty, or held in a horizontal position during the discharge thereof, or inclined upward or downward, the ends of the tube 27 are provided with gravity- 20 seated inwardly closing and outwardly opening valves 38, 39, consisting of balls connected by a rod 40 extending through the tube and the said balls adapted to coöperate with valve seats formed at or connected 25 to the ends of the tube 27.

In operation assuming the syringe to be held in a horizontal position, as the piston is drawn out it will unseat the valve 28 drawing liquid through the port 9 into the piston chamber in front of the piston, the piston at the same time ejecting air which may be in back of the piston out through the outlet port 13, tube 15, chamber 16, port 11, tube 17, and the reservoir outlet. Upon 30 the piston being moved inward it will eject the liquid previously drawn into the cylinder in front of the piston out through port 11' unseating the valve 12, through chamber 16; port 11 and tube 17 connected 35 with the reservoir outlet, and simultaneously therewith unseat the valve 29 and draw liquid from the reservoir through the port 10 into the cylinder in back of the piston, which liquid is discharged from in back of 40 the piston during the next outward movement of the piston through port 13 as hereinbefore described. This operation is repeated so long as the piston is reciprocated. The outlet 4 of the reservoir is preferably restricted, and as the liquid is drawn 45 from the reservoir and injected into the chamber or tube 17, this volume of liquid being greater than what can be ejected through the restricted outlet, the incoming liquid will tend to create a pressure in said 50 chamber and thereby increase the force of the ejected stream.

The present application is a continuation of an application filed by me February 28, 60 1916, bearing the Serial No. 80,796.

Having thus described my invention, I claim:

1. In combination with a receptacle, a

pump comprising a piston, a cylinder in which said piston is arranged to reciprocate, 65 and divided by said piston into two compartments, valved inlet connections from the receptacle to said compartments, an outlet means to discharge the liquid withdrawn from the receptacle, a casing arranged adjacent to said outlet means, said casing containing a chamber adapted to communicate with said outlet means, and having a port leading to the adjacent cylinder compartment, a valve movable in said chamber 75 lengthwise of the pump and controlling said port, and a valved connection extending from said chamber to the other compartment of the pump cylinder.

2. In a syringe, the combination with a 80 reservoir having an outlet, of a cylinder therein of less length than the reservoir and connected at opposite ends with the reservoir; outlets at opposite ends of the cylinder; means to connect said outlets to the reservoir outlet; a piston to reciprocate in the cylinder; and a rod to reciprocate the piston from the exterior of the cylinder and reservoir, and said piston during the reciprocation thereof alternately drawing liquid from 90 the reservoir to the opposite ends of the cylinder, and alternately discharging the liquid from opposite ends of the cylinder through the cylinder outlets and connected reservoir outlet.

3. In a syringe, the combination with a reservoir having an outlet, of a cylinder therein connected at opposite ends to the reservoir; an outlet at one end of the cylinder; an outlet at the opposite end of the cylinder; a casing to connect said outlets to the reservoir outlet; and a piston to reciprocate in the cylinder, substantially as and for the purpose specified.

4. In a syringe, the combination with a 105 reservoir having an outlet, of a cylinder therein; intakes at opposite ends of the cylinder to connect the cylinder to the reservoir; valves in said intakes opening into the cylinder and closing outward therefrom; a 110 valved port in one end of the cylinder connected to the reservoir outlet; a valved port in the opposite end of the cylinder; means to connect said latter port to the cylinder port connected to the reservoir outlet; and 115 a piston to reciprocate in the cylinder, substantially as and for the purpose specified.

5. In a syringe the combination with a reservoir having an outlet, of a cylinder therein having a head at each end and by 120 means of one of which heads it is mounted in the reservoir; an intake to the cylinder in each cylinder head to connect the cylinder with the reservoir; valves for said intakes opening into the cylinder and closing outward therefrom; a port in one head of the

cylinder; a valve in said port closing into the cylinder and opening outward therefrom; a tube connecting said port with the reservoir outlet; a port in the opposite head of the cylinder; a valve in said port closing into the cylinder and opening outward therefrom; a tube exterior of the cylinder

to connect said latter port with the port in the opposite head connected to the reservoir outlet; and a piston to reciprocate in the cylinder, substantially as and for the purpose specified. 10

GEO. T. PEARSONS.
